Aug. 12. 1831

William Williams of Buckingham Township, Pennsylvania
Sellers Patent.

The Schedule referred to in this Letter Patent, and making part of the same, containing a description in the words of the said William Williams, himself, of his improvement, being a machine for hulling and cleaning clover seed.

Be it known that I, William Williams, of Buckingham Township, Bucks County, Pennsylvania, have made an improvement, being a machine for hulling and cleaning clover seed, which is described as follows. This machine consists of the following parts. 1. The Frame. 2. The toothed cylinder. 3. The curved bed of teeth and grater. 4. The fan. 5. Flap, or opening for the wind, clover seed, gravel, dirt, &c to pass. 6. The Fader. 7. The Hopper. 8. The gearing.

1. The frame is constructed of four posts, four sills, and four top pieces, sufficiently large and strong for the purposes intended. The posts are to be cut opening to receive the head blocks to be hereafter described. 2. The toothed cylinder. This cylinder is about 4 feet long and 2 feet 4 inches diameter, and is constructed by making two round heads and nailing strong rods of wood on them, and then covering the cylinder with sheet iron, riveted fast. Nails are to be punched in the sheet iron in rows, about $\frac{3}{8}$ inch apart, and teeth about $\frac{3}{8}$ inch long cut to a proper angle, are driven in rows, all around the cylinder. The axle of the cylinder lies on guides, in moveable head blocks, which can be moved up and down, or backward and forward, by means of wedges or keys in the openings cut in the frame.

3. The curved Bed of teeth and grater. A half circle made to the same curvature as the cylinder, enclosing one half of the cylinder and one fourth of the cylinder forming the lower side is covered with another segment of the curved bed and grater. The first part or semicircle is covered with sheet iron filled with teeth of the same

same size and figure as those of the cylinder. The ~~second~~ part, or quarter circle is made of steel iron, follow also with teeth in the upper part and a greater about 17 inches in width, in front, and and is movable to and from the cylinder. 4. The fan, is made in the usual form, and is placed at the hinder part of the machine, so as to operate in blowing the clover seed &c along the flue to be hereafter described.

5. The flues or openings for the wind. Above seed, gravel, dirt &c. to pass, a flue from the fan leads towards the hopper of the machine. There is also another passage or opening nearly at right angles with the first, to admit the gravel or dirt to fall down. The first flue after passing the passage for the dirt &c. conveys by the wind, the clover seed, to the cylinder.

6. The feeder. This is constructed by making a common feeder of cloth or leather to pass over two rollers, placed on the top of the machine. A pulley is fixed on the axis of one of them for giving motion.

7. The Hopper. This is made in the usual form; is open at top to receive the clover seed, and has a passage to let the seed fall upon the cylinder, and an opening corresponding to the flue from the fan. It is placed on the top of the machine.

8. The gear. One pulley is placed on the side of the cylinder, another on the side of the fan, and another on the side of the feeder. A strap or band passes over these pulleys and motion is given to the machine by the application of any power.

Operation. The clover seed is placed upon the feeder, and motion being given to the machine by animal or other power, it descends into the passage where it meets the blast from the fan: the gravel, dirt, &c. being heavy, fall down the vertical opening, and the clover is blown through the opening of the hopper into it: the clover then descends to the cylinder where the seed is rubbed out between the teeth of the cylinder and sand and dirt: it is further rubbed out by the grates in front. The cylinder can be raised or depressed, or moved backward or forward, at pleasure by means of the wedges and head blocks. This machine separates, back from clover seed, on account of the buck horn being heavier and falling down with the dirt, &c. and leaves all hard and heavy substances that would injure the teeth of the machine are separated from the clover seed.

What I claim as my invention is the peculiar arrangement of the several parts of the described machine for hulling and cleaning clover seed; and particularly in applying the wind of a fanning machine to separate the clover seed from gravel, bark, horn, and all heavy hard substances, which would injure the teeth of the machine. For a further illustration of my Invention I refer to the model and drawing of the same deposited in the Patent Office.
